ATTORNEY.

UNITED STATES PATENT OFFICE

GEORGE E. FRITTS, OF HARBOR CITY, CALIFORNIA

SUCKER-ROD ELEVATOR

Application filed April 2, 1928. Serial No. 266,732.

My invention relates to rod-supporting devices, and more particularly to a sucker rod elevator.

The conventional deep oil-well is equipped with a pump suspended in the well on a pump tubing, this tubing being in turn suspended from the surface of the ground. The pumping action is obtained through a plunger in the pump, this plunger being reciprocated by a string of sucker rods extending upward through the pump tubing. This string of sucker rods is formed of lengths joined together by suitable couplings, these lengths having enlarged head portions at each end thereof. In raising the sucker rods from the well, it is necessary to suitably grasp the upper end of the rod at the surface of the ground.

It is an object of my invention to provide a device which will grasp and support these sucker rods, although it should be understood that my invention is equally applicable to supporting pipes, etc. both in the oil well industry and in other arts. Thus, I shall particularly describe my invention with relation to the oil-well industry for the purposes of clearness and definiteness without limiting myself thereto.

A further object of my invention is to provide a rod-supporting device which will automatically close when a rod is moved thereinto.

Still another object of my invention is to provide a device having a rotatable and axially movable gate which swings into locked position when a rod is placed in the device, this gate being easily moved into an open position to release said rod.

Still a further object of my invention is to provide a rod-supporting device which cannot be opened when a rod is supported therein.

Further objects and advantages of my invention will be made evident hereinafter.

Referring to the drawings,—

Fig. 1 is a utility view illustrating my invention as applied to an oil-well.

Fig. 2 is a top view of the elevator of my invention taken on the line 2—2 of Fig. 1.

Fig. 3 is a front view taken in the direction of the arrow 3 of Fig. 2.

Fig. 4 is a cross-sectional view taken on the line 4—4 of Fig. 2, illustrating the elevator in locking position.

Fig. 5 is a view similar to Fig. 4 illustrating my elevator in disengaged position.

Fig. 6 is a sectional view taken on the line 6—6 of Fig. 2.

Fig. 7 is a rear view taken in the direction of the arrow 7 of Fig. 2.

Fig. 8 is a horizontal sectional view taken substantially on the line 8—8 of Fig. 7.

Fig. 9 is a sectional view taken on the line 9—9 of Fig. 6.

Fig. 10 is a detailed sectional view taken on the line 10—10 of Fig. 8.

Referring to Fig. 1, I illustrate an oil-well 10 in which suitable casings 11 and 12 have been set. Extending through the inner casing 12 is a pump tubing 13 which extends downward to a pump 14 which is supported therein. One type of pump well-known in the art has a plunger which is reciprocated by a string of sucker rods 15 extending upward to the surface of the ground, these sucker rods being adapted to raise the pump from the well when drawn upward. In Fig. 1, I have illustrated only one sucker rod supporting the pump 14, this sucker rod being indicated by the numeral 16. This sucker rod has upper and lower head members 17 and 18 respectively which are larger in diameter than the body of the sucker rod.

Adapted to support the sucker rod 16 and the pump 14 is an elevator 20 incorporating the features of my invention. This elevator comprises a body 21 having trunnions 22 extending outward therefrom. The trunnions 22 are aligned on an axis A—A indicated in Fig. 3, this axis being above the central horizontal axis of the body 21. The trunnions 22 provide a convenient means for attaching a bail or other supporting member 23 to the elevator 20, this supporting member having eyes 24 which surround the trunnions 22. These eyes are held in place by washers 25 and cotter pins 26, as best shown in Figs. 2 and 3. The supporting member 23 is, in turn, supported on a hook 28 of a travelling block 190

29, this travelling block being vertically movable relative to the well 10.

The mechanical details of the elevator 20 of my invention may best be understood by reference to Figs. 2 to 10 inclusive. Referring particularly to Figs. 2, 5, 8, and 9, the body 21 has an opening 30 therein, this opening communicating with the front of the body and being flared to permit the easy movement 10 of the sucker rod 16 into this opening. The inner end of the opening 30 is formed on a diameter substantially equal to the diameter of the sucker rod.

The opening 30 is adapted to be closed by a 15 gate 33, this gate being pivotally secured to the body 21 on an axis B—B, shown in Figs. 4 and 5. The gate 33 has a gate body 34, and extending from the upper end of this body is an upper engager 35 of a shape best shown in 20 Figs. 2 and 5. A similar lower engager 36 is formed near the lower end of the gate body 34. Each of these engagers comprises a catch portion 38 and a hub portion 39. From an examination of Fig. 5, it will be clear that 25 the hub portion of the lower engager 36 is much thicker than the hub portion of the upper engager. In plan view, the shapes of the upper and lower engagers 35 and 36 are identical, these views being shown respectively in 30 Figs. 2 and 8. Each engager has a channel 40 formed therein, this channel being complementary to the inner end of the opening 30 so that this inner end and the channel 40 cooperate to provide a rod space 41 when the 35 gate is in closed position, indicated in Figs. 2, 3, 4, 5, 6, 8, and 9. The hub portions 39 of the engagers 35 and 36 are circular in contour, as shown in Figs. 2 and 8.

The gate 33 moves into its locked position, 40 shown in full lines in the drawings, by rotating about the axis B—B in a position indicated in Fig. 5. This rotation is permitted by a groove 43 formed of such a shape as to permit the catch portion 38 of the lower engager 36 to move therein when the gate is 45 pivoted about the axis B—B. This groove is best shown in Fig. 8. In thus pivoting about this axis, the hub portion 39 of the lower engager 36 turns in a recess 45 formed 50 in the body 21. During this closing movement, the upper engager 35 lies entirely above the body 21, and the gate 33 is held in its upper position shown in Fig. 5 through engagement 55 between the engagers 35 and 36 and portions of the body 21.

When the gate 33 has been moved into its closed position, it may drop downward into a locking position indicated in Fig. 4. This downward movement of the gate 33 is permitted by means of upper and lower cavities 46 and 47, these cavities being adapted to respectively hold the upper and lower engagers 35 and 36. As best shown in Figs. 2 and 8, the upper and lower cavities are shaped to 60 conform to the outline of the engagers 35 and

36 so that when the gate 33 is in its lower position indicated in Fig. 4, these engagers snugly fit in their respective cavities, thus preventing an opening of the gate.

This rotation of the gate 33 on the axis B—B and the axial movement thereof along this axis, is permitted by means of a tubular member 50 which is disposed concentric with the axis B—B. This tubular member is threaded, as indicated by the numeral 51, 70 into a lower plate 52 extending between the lower cavity and the lower face of the body 21. This tubular member 50 extends upward through this lower cavity and through the recess 45, being held in an opening 80 formed in a ledge 53 which separates the upper cavity 46 and the recess 45. This ledge also has an opening 54 concentric with the axis B—B, this opening being of a suitable diameter to journal a bolt 55 which extends through the tubular member 50 and is threadedly received in the hub portion 39 of the upper engager 35, as best shown in Figs. 4 and 5. This bolt 55 has a head 57 of such a diameter as to be journalled by 90 the interior of the tubular member 50. A spring 59 is compressed between the head 57 and the ledge 53, this spring acting to force the gate 33 into locking position at the instant this gate reaches its full closed position shown in full lines in the drawings.

The gate 33 is adapted to be again moved into its upper position, preparatory to removing the rod from the opening 30 by means of a mechanism best illustrated in 100 Figs. 2 to 9 inclusive.

There are various methods by which this return of the gate into disengaged position might be effected, but I prefer to utilize a sector gear 62, the teeth of which are 105 adapted to engage teeth 63 cut on the circular edge of the hub portion 39 of the lower engager 36. The teeth 63 are cut on a circular contour as indicated in Fig. 8, so that the gate may be opened and closed while the teeth of the sector gear 62 and the teeth 63 are in engagement. The sector gear 62 is secured to a shaft 65, this shaft extending through an opening 66 in the body 21 and being journalled therein. The outer end of this shaft 65 is attached to a crank 67 which is, in turn, pivotally secured to an arm 68 having a grip 69 thereon. The upper and lower ends of this grip are adapted to fit in upper and lower channels 70, these channels being formed in top and bottom plates 71 and 72 respectively extending from the body 21. The relationship between the grip 69 and the plates 71 and 72 is such that this grip may be moved from its full line position shown in Fig. 7 into its dotted line position indicated by the numeral 73, the grip 69 sliding in the channels 70 during this movement. A suitable stop member 74 is threadedly received by a web 75 extending 110

115

120

125

130

135

140

between the top and bottom plates 71 and 72 respectively, this stop determining the maximum movement of the grip 69. When this grip is moved from its full line position into its dotted line position 73, the crank 67 is so moved as to rotate the shaft 65 and the sector gear 62. When this is moved, the sector gear moves the gate 33 into its uppermost position, indicated in Fig. 5, against the action of the spring 59. When in this uppermost position the gate can easily be swung open by withdrawing the sucker rod from the opening 30.

Formed at the lower end of the gate body 34 is a boss 78 which is of such a length that its lower face just clears the lower plate 52 when the gate 33 is in its upper position and is moved into an open position. A vertical hole 89 is drilled upward in the boss 78, this hole having a compression spring 90 therein which bears against a ball 91. The lower end of the hole 89 is suitably peened to retain the ball 91 in the hole 89 so that when in a lowermost position this ball extends slightly below the lower surface of the boss 78. A depression 92 is formed in the lower plate 52 to receive this ball 91 in such a manner as to resiliently hold the gate open once it assumes this position. An inward movement of the gate is easily possible, the ball 91 leaving the depression 92 at this time.

The open position of the gate 33 is indicated by dotted lines 94 of Figs. 2, 6, 8, and 9. It is desirable that the gate 33 be swung into closed position, indicated by full lines, when the sucker rod 16 is moved into the opening 30. This automatic closing of the gate I accomplish by means of the mechanism best shown in Figs. 2, 6, and 9. Referring to these figures, the central portion of the gate body 34 has an arm 95 extending therefrom, this arm being moved in a channel 96 of the body 21 when the gate 33 is pivoted about the axis B-B or is moved therealong. This arm 95 assumes a position indicated by dotted lines 97 when the gate is in open position, so that the rod 16 engages this arm when entering the opening 30.

This arm may, in itself, be used as a means for moving the gate into locking position, but I have found it more convenient and satisfactory to pivot a link 98 to the arm 95 in a position shown in Fig. 9. This pivotal connection is made by bifurcating the end of the link 98 and passing a pin through this end and the arm 95. The free end of the link 98 is movable in a passage 99 of the body 21, this end never completely leaving this passage during the time that the gate 33 is being swung from one position into another. As the gate nears its closed position, the sucker rod 16 engages the link 98 rather than the arm 95. The relationship be-

tween the link and the arm is such that this engagement of the link and the sucker rod closes the gate more easily than would the simple engagement of the sucker rod and the arm 95.

The operation of my invention is as follows:

When the gate is in open position, indicated by dotted lines 94, the sucker rod 16 is moved into the opening 30. This rod engages the arm 95 when in its dotted line position 97 and tends to turn the gate in an anti-clockwise direction about the axis B-B after releasing the ball 91 from the depression 92. As the sucker rod 16 is moved still further in the opening 30, this rod engages the link 98 which continues the anti-clockwise rotation of the gate 33 until the upper and lower engagers 46 and 47 may drop into their respective cavities due to the action of the spring 59. At this time the sucker rod is locked in the elevator 20 and the rod may be either raised or lowered by moving the travelling block 29. The rod 16 is not tightly clamped in the rod space 41, but the weight thereof causes the head portion 17 of the sucker rod to engage the upper face of the body 21 and the gate 33. In order to prevent excessive wear on the upper face of the body 21, I provide a wear plate 102 suitably held in a recess 103 by countersunk screws 104.

When it is desired to release the rod, the elevator 20 is lowered relative to the head 17 and the operator moves the grip 69 into its dotted line position, thus raising the gate 33. At this instant the operator draws the sucker rod from the opening 30, this movement pivoting the gate 33 about the axis B-B in a clockwise direction. This movement of the gate 33 is continued until the gate is entirely opened at which time the ball 91 engages the depression 92.

The advantages of my invention over previously used types are numerous. In the first place, I accomplish a complete enclosure of the sucker rod throughout the full thickness of the elevator body. The gate 33 when in locked position is supported at four points, thus insuring safety against premature opening under abnormal pressure. By placing the trunnions 22 above the horizontal center line of the body 21, I secure a perfectly balanced structure, both when the sucker rod is supported from the elevator and when this elevator is not in use.

The gate 33 may be moved into its upper position by the use of only one hand, thus leaving the operator's other hand free to move the sucker rod into the opening 30, the locking action taking place automatically when this rod is moved sufficiently into the opening.

My elevator is of extremely rugged construction and by using hardened parts I have found that its life is very long.

I claim as my invention:

1. In a sucker rod elevator, the combination of: a body, a rod, said body being movable relative to said rod, and having an opening to receive said rod; a gate hinged to said body to close said opening when said rod is in place; an arm carried by said gate; and a link pivoted to said arm, said arm and said link cooperating to move said gate into closed position.
2. In a sucker rod elevator, the combination of: a body, a rod, said body being movable relative to said rod, and having an opening to receive said rod; a gate hinged 15 on an axis of said body; means engaging said rod as it moves into said opening to swing said gate into closed position; and means for moving said gate along said axis to lock it in closed position.
3. In a sucker rod elevator, the combination of: a body, a rod, said body being movable relative to said rod, and having an opening to receive said rod; a gate hinged on an axis of said body; means engaging said rod 25 as it moves into said opening to swing said gate into closed position; means for moving said gate along said axis to lock it in closed position; and means for returning said gate along said axis, said rod opening said gate 20 in moving from said opening.
4. In a sucker rod elevator, the combination of: an elevator body, said body having a cavity therein; a gate pivoted relative to said body; an engager on said gate; a spring 35 operated mechanism for moving said engager into said cavity when said gate reaches a closed position; and mechanism for raising said engager from said cavity.
5. In a sucker rod elevator, the combination of: an elevator body, said body having a cavity therein; a gate pivoted relative to said body; an engager on said gate; a spring 40 operated mechanism for moving said engager into said cavity when said gate reaches a closed position; teeth cut on said gate; a gear meshing with said teeth to move said engager from said cavity; and means for turning said gear.
6. In a sucker rod elevator, the combination of: an elevator body, said body having a pair of cavities therein; a gate pivoted relative to said body; a pair of engagers on said gate; a spring operated mechanism for moving said engager into said cavity when said 55 gate reaches a closed position; and mechanism for raising said engager from said cavity.
7. In a sucker rod elevator, the combination of: an elevator body, said body having a groove and a recess therein; a gate; a pair of engagers on said gate; a pair of hub portions on said gate; means for pivoting said hub portions to said elevator body whereby said gate may be moved into closed and open 60 positions; and cavities in said body into

which said engagers are moved when said gate is in a closed position.

8. In a sucker rod elevator, the combination of: an elevator body, said body having a groove and a recess therein; a gate; a pair of engagers on said gate; a pair of hub portions on said gate; means for pivoting said hub portions to said elevator body whereby said gate may be moved into closed and open 70 positions; cavities in said body into which said engagers are moved when said gate is in a closed position; and mechanism for releasing said engagers from said cavities.
9. In a sucker rod elevator, the combination of: an elevator body, said body having a groove and a recess therein; a gate; a pair of engagers on said gate; a pair of hub portions on said gate; means for pivoting said hub portions to said elevator body whereby said gate may be moved into closed and open 75 positions; cavities in said body into which said engagers are moved when said gate is in a closed position; and mechanism for releasing said engagers from said cavities.

- 80
- 85
- 90
- 95

10. In combination: a body having a recess therein; a gate having hub portions thereon; a tubular member extending through said recess and journaling in one of said hub portions; and a bolt slidable in said tubular member, said bolt being threadedly received by the other of said hub portions.

In testimony whereof, I have hereunto set my hand at Los Angeles, California, this 26th day of March, 1928.

GEORGE E. FRITTS.
